UNITED STATES PATENT OFFICE

FORDYCE CHARLES JONES, OF PADDINGTON, LONDON, ENGLAND

BREAST SUPPORT

Application filed December 12, 1929, Serial No. 413,557, and in Great Britain November 2, 1928.

This invention relates to breast-supporting devices and more particularly to the kind of device which comprises a pair of substantially inextensible pockets connected together by a front insert of elastic, said device having means, such as wrap-round members and/or shoulder straps, for securing it to the wearer.

The present invention provides an article of this nature having an elastic area or inset 10 (or areas) so shaped and arranged between a pair of non-extensible breast covering areas or pockets, that the breasts are adequately supported without undue pressure, whilst the device lies snugly and flatly against the body 15 at the surrounding areas, especially forming a perfect resilient and close fit between the breasts at or below the sternum.

The invention consists in a pair of pockets joined together at a point or short seam at 20 the front, or integrally made in one piece and having an inverted V-shape opening between the pockets containing a resilient insert constituting an elastic diaphragm.

The elastic material used is advantageously, 25 although not necessarily, cut or moulded sheet rubber, and another advantage of such an insert as described later, is the slight expansion permitted over the diaphragm when breathing. At this central area, also, the resilience of the elastic area, and its close-fitting 30 design, tends to flatten the plump part sometimes occurring with certain types.

In order that the invention may be clearly 35 understood, some embodiments thereof will be described in greater detail with the aid of the accompanying drawings wherein:—

Figure 1 shows one embodiment, spread out.

Figures 2 and 3 are front and back views 40 respectively of the form according to Figure 1 when in position on the wearer.

Figure 4 is a view showing the main part of a further embodiment, side extensions and various straps having been omitted for convenience.

Figure 5 is a perspective view of a further embodiment.

Referring firstly to Figures 1, 2 and 3, the breast-support, according to the invention, 50 comprises broadly a pair of non-extensible

breast covers or pockets 1 and 2 adapted to be held in position by tapes or straps whereby they are neatly fitted close to the breasts all round including the region of the sternum therebetween. For instance, silk or other 55 fabric supports of approximate rhombic outline as shown may be relatively disposed to lie with a corner (3 and 4 respectively) of each attached together, presenting two upwardly projecting corners with a flattened V 60 or U opening 13 therebetween at the top (or this may be cut to present a straight, or other required design at the top), and an inverted V at the bottom. Shoulder straps 5 are attached at each side, viz.:—from an upper corner 3 (or 4) to an outside corner 6 (or 7). 65 Waist or body straps or tapes 8 and 9 (elastic or partly elastic if desired) are also attached one at each side; these latter are for taking round the back of the body and attaching to 70 the front of the device.

The inverted V opening between the two breast covers 1 and 2 is filled in with a triangular insert of rubber 10, the two lower corners of the base thereof being eyeleted, 75 tabbed, or otherwise formed as at 11 and 12 as attaching means for the aforesaid waist straps 8 and 9, the left-hand waist-strap 8 (locking from the front)—see Figure 1 especially—passing round the wearer's back and 80 being secured to the right-hand corner 12 of the insertion 10, and right-hand strap 9 being secured at 11. Figures 2 and 3 illustrate this fastening method.

The said breast-covers have been described 85 as rhombic for convenience of description; they may be square, rectangular, round, oval or otherwise shaped to leave the upper V or desired configuration at the top, and the inverted V-shape lower opening to take the 90 insert. In the alternative shapes, the straps and tapes would be secured at appropriate places to produce a close fitting equivalent to the fitting when attached at corners as described.

The covers 1 and 2 are tucked or prepared 95 in any way to form them into pockets, and when straight edges 14 and 15 are presented at the top to form the V or U, the slope of the lines 14 and 15 may be such that it in- 100

clines to the horizontal at an angle, which, if the edge 14 or 15 were produced, it would lie above the outside (i. e. above) corner of the garment 6 or 7 towards which it is inclined. This is a refinement of construction, 5 however, of an optional nature.

In addition to the central insert of rubber or the like 10 already mentioned, there may be attached to the outside of the breast-covers respectively, an "armpit" resilient piece, preferably triangular in shape, point directed outwardly, and base (curved or not) attached to the breast-cover. 10

Figure 4 shows an elastic insert in the form 15 of strips 16 replacing the sheet 10 of Figure 1. In such a modification, the bottom strip 16 only would be employed, the rest remaining either open, or filled in with the pocket material pleated to permit extension.

Figure 5 illustrates an alternative method 20 of fastening, dispensing with the long cross-over ends 6 and 7 and straps 8 and 9 (see Figure 3), and employing a simple back fastening 17.

When a breast-support, as illustrated, is 25 put under tension by pulling along the bottom thereof, such as by pulling on the points 11 and 12, the diaphragm 10 tightly and snugly flattens or fits the body of the wearer 30 between the breasts, and the upwardly converging sides of the insertion 10 assume a concave curve, fitting the respective breast. At the same time, the inextensible pockets 35 form an adequate corrective support with no elastic pressure directly applied to or under the breasts.

I claim:—

A breast support comprising a pair of substantially inextensible members having 40 breast supporting pockets and stitched together at their upper inner corners to provide a substantially inverted V-shaped opening therebetween and the ends of said members being tapered into strip-like formation 45 to provide body encircling attaching strips, a substantially triangular elastic section secured in said opening and having integral ears provided with button holes, and buttons on the ends of said straps for entering said 50 button holes.

In testimony whereof, I have affixed my signature hereto this 26th day of November, 1929.

FORDYCE CHARLES JONES.
